(Cl. D71—1)

To all whom it may concern:

Be it known that we, Herbert L. Bowers and Robert A. Wolf, citizens of the United States, residing at 121 Southwood Drive and 48 Woodcrest Avenue, Kenmore, county of Erie, State of New York, have invented a new, original, and ornamental Design for an Airplane, of which the following is a specification, reference being had to the accompanying drawings, forming a part thereof.

Figure 1 is a top plan view of an airplane showing our novel design;

Figure 2 is a front elevational view;

Figure 3 is a side elevational view; and

Figure 4 is a rear elevational view thereof.

We claim:

The ornamental design for an airplane, as shown.

HERBERT L. BOWERS.
ROBERT A. WOLF.
